UNITED STATES PATENT OFFICE.

FRANK P. LONGCOR, OF KEOKUK, IOWA.

TRACK-LEVEL.

1,341,377.

Specification of Letters Patent. Patented May 25, 1920.

Application filed July 20, 1916. Serial No. 110,400.

To all whom it may concern:

Be it known that I, FRANK P. LONGCOR, a citizen of the United States, residing at Keokuk, in the county of Lee and State of Iowa, have invented certain new and useful Improvements in Track-Levels, of which the following is a specification.

My invention relates to measuring devices or instruments and contemplates primarily an improved combined level, gage, and measuring device of a construction, combination and arrangement of parts hereinafter more particularly described and claimed.

In describing my invention in detail reference will be had to the accompanying drawings wherein like characters denote like or corresponding parts throughout the several views, and in which:

Figure 1, is an elevation of my improved combined track level and gage,

Fig. 2, is a top plan view,

Fig. 3, is an elevation, the opposite side from that of Fig. 1 being illustrated,

Fig. 4, is a section on the line 4—4 of Fig. 3,

Fig. 5, is a section on the line 5—5 of Fig. 3,

Fig. 6, is a fragmentary perspective view illustrating the manner in which the sighting board is withdrawn, and

Fig. 7, is a similar view illustrating the manner in which the track gage bar may be moved.

Referring to the drawings by numerals, 1 designates the stock or body of my improved device. A spirit level 2 is made a part of the stock or body 1 to indicate, when the device is placed transversely of a railway track, whether or not the rails lie true and level.

One face of the stock or body is cut away as indicated at 3 for the reception of a gage bar of a size and construction to snugly fit the space 3 in the manner illustrated in Fig. 3. Extensions 5 are formed, one at each end 45 of the gage bar 4, said extensions, when the gage bar is moved or extended, fitting between the railway rails to thus gage and accurately determine whether or not the mentioned rails lie parallel. Retaining

strips or bands 6 (preferably three in number), are fastened as indicated at 7 to the stock or body 1, and are utilized as a fastening means for the gage bar 4. A block 8, if desired, may be utilized to releasably hold

55 the gage bar 4 in raised position against

movement in the manner illustrated in Fig. 3 when said gage bar is not in use. By removing the block, the bar will descend so as to project the extensions 5 thereof below the lower edge of the stock 1 to the position 60 shown in Fig. 7.

At one end of the stock or body 1 and operating in a transverse groove 9, is a graduated strip or bar 10 of a length to extend beyond the terminals of said groove. A retaining strip 11 is utilized to hold said bar 10 in said groove. In use, the block 8 is removed to permit the bar 4 to fall so that its terminals 5 may depend below the lower edge of the board. One terminal 5 is engaged against the inner surface of the tread of one rail, and the opposite end of the board is then moved upwardly or downwardly, as the case may be, until the level 2 indicates that the horizontal position of the 75 board is correct. The bar or scale 10 is then dropped until its lower end rests upon the top surface of the tread of the rail, thus enabling the operator to ascertain the exact difference in elevation of one rail over the 80 other.

Coming now to a description of the sighting board, 12 designates the mentioned board in its entirety, the same, as illustrated in Fig. 1, being normally held in a recess or 85 cut-out portion 13 formed in the stock or body 1 upon the opposite side thereof from that receiving the gage bar 4. The retaining strips or bands 6 are conjunctively utilizable as a means for holding not only the 90 gage bar 4 in place, but as a holding means for the sighting board 12. If desired, the mentioned board may be longitudinally graduated as at 12' to designate in inches and fractions thereof a particular "rise" 95 necessary in leveling a railway track in the laying thereof.

In use, the sighting board is placed transversely of the rails and rested at each end upon one of the rails. The sighting board is 100 located on the rails at the point last leveled, and the operator assumes a recumbent position, adjacent one of the rails at a point some distance from the sighting board. Previous to assuming this position, however, 105 a block is placed upon the rail at the lowermost point thereof, and another block is placed upon the same rail at a point adjacent the position of the operator. The operator then glances across the top of the first block 110

and notes the points on the sighting board coinciding with the top surface of the second block so that the exact amount of depression of the low point in the rail can be noted.

5 From the foregoing, taken in connection with the accompanying drawings it is evident that my combined device may be conjointly used as a means to determine the proper spacing of the railway rails, as a 10 means to accurately gage the rise of one rail above the other on a curve, and as a means to level the track during the laying thereof, that each of the various parts is so correlated with the stock or body 1 as to form, when 15 not in use, substantially a part thereof; and that by terminating the space 3 formed in the stock or body 1 short of the ends thereof, longitudinal movement of the gage bar 4 in the space 3 cannot under any circumstances 20 be obtained.

It will be understood that the above description and accompanying drawings comprehend only the general and preferred embodiment of my invention and that various 25 minor changes in details of construction, proportion and arrangement of parts may be made within the scope of the appended

claims and without sacrificing any of the advantages of my invention.

Having thus fully described my invention, 30 what I claim as new and desire to secure by Letters Patent, is:

1. A device of the character described comprising a board having a recess adjacent its lower marginal edge, a gage bar slidably 35 mounted in said recess, a transverse groove at one end of the board, a scale slidably mounted in said groove, and means adapted to normally hold the gage bar in a raised position.

2. A device of the character described comprising a board having a recess along its lower edge, a gage bar slidable therein, said bar having extensions formed integral therewith at each end, a scale adjustably connected to one end of the board, and means adapted to normally hold the said gage bar in a raised or inoperative position.

In testimony whereof I affix my signature in presence of two witnesses.

FRANK P. LONGCOR.
